CLAIM

The ornamental design for whiteboard with photocopier, as shown and described.

DESCRIPTION

FIG. 1 is a front elevational view of whiteboard with photocopier showing our new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a front and left side perspective view thereof;

FIG. 8 is a sectional view thereof, taken along line 8—8 of FIG. 1;

FIG. 9 is a front and left side perspective view thereof; and

FIG. 10 is a front and left side perspective view thereof, shown with the board position rotated to a horizontal position.

The broken line showing of the indicia and the sheet of paper in FIG. 9 is for illustrative purposes only and forms no part of the claimed design.
